SOUND RECORDING TAPE REEL

Roger F. How and Donald S. Whitnah, St. Paul, Minn., assignors to Minnesota Mining & Manufacturing Company, St. Paul, Minn., a corporation of Delaware

Application February 26, 1949, Serial No. 1,096

Term of patent 14 years

(Cl. D26—14)

To all whom it may concern:

Be it known that we, Roger F. How and Donald S. Whitnah, both citizens of the United States, residing at St. Paul, in the county of Ramsey and State of Minnesota, have invented a new, original, and ornamental Design for a Sound Recording Tape Reel, of which the following is a specification, reference being had to the accompanying drawing, forming a part thereof.

Figure 1 is a side elevational view of a sound recording tape reel, showing our new design;

Figure 2 is an end elevational view; and

Figure 3 is a sectional view along the line 3—3 of Figure 1.

We claim:

The ornamental design for a sound recording tape reel, as shown.

ROGER F. HOW.

DONALD S. WHITNAH.
